UNITED STATES PATENT OFFICE.

FRANK P. BLAIR, OF TOLEDO, AND CHESTER L. DOWS AND GEORGE S. MERRILL, OF CLEVELAND, OHIO; SAID DOWS ASSIGNOR TO SAID BLAIR AND MERRILL.

INDICATING DEVICE.

1,340,145.

Specification of Letters Patent.

Patented May 18, 1920.

Application filed July 24, 1919. Serial No. 312,888.

To all whom it may concern:

Be it known that we, FRANK P. BLAIR, of Toledo, county of Lucas, State of Ohio, CHESTER L. Dows, of Cleveland, county of 5 Cuyahoga, State of Ohio, and GEORGE S. MERRILL, of Cleveland, county of Cuyahoga, State of Ohio, citizens of the United States, have invented certain new and useful Improvements in Indicating Devices, of which

10 the following is a specification.

Our invention relates to indicating devices and more particularly to such devices for use in hotels, theaters, offices and similar places. While our invention may be readily 15 used in other places, we have described it with reference to hotels in order to simplify the description. However, those skilled in the art will readily see how our invention may be utilized as a vacant seat indicator 20 for theaters, absent employee indicator for time clock systems and for other like purposes.

At present, when a guest registers at a hotel, the clerk must look at his room rack 25 to determine which rooms are vacant before he can assign the guest a room of his choice. The room rack consists of card holders, one to each room, which are disposed in as small a space as possible. When a guest is assigned to a room, a card is placed in the corresponding holder and the card is removed when the guest leaves. In hotels which have but few rooms, the room rack is small and a search for a room usually 30 does not consume sufficient time to inconvenience the guest. In larger hotels where there are many rooms, and consequently the room rack is large, this search consumes some time which is annoying especially 35 when there are a number of people waiting to register. Furthermore, rooms which are vacant may be overlooked by the clerk or he may assign two guests to the same room because a card was not immediately placed 40 in the room rack upon assignment of the room to a guest. Practical operation of this system depends upon the immediate insertion of the card in the corresponding holder when a room is assigned.

45 Our object is to overcome the difficulties just described. According to our invention, the register clerk may quickly determine at a glance which rooms are vacant without overlooking any. Furthermore, if 50 no rooms of the guest's choice of price are

available, the register clerk may, at the same time, locate vacant rooms of a price nearest to the choice. The successful operation of our invention does not depend upon a card or check being inserted in the rack 60 immediately upon the assignment of the room to a guest. Moreover, according to our method the apparatus may be quickly and conveniently checked up to locate faults or errors. 65

Our invention consists in providing a plurality of receptacles for the room checks or cards, in providing a plurality of indicators each corresponding to a card or check receptacle and in providing means whereby 70 the insertion or removal of a check will cause a suitable indication to appear on the corresponding indicator. We prefer to accomplish this electrically and to utilize electric incandescent lamps as the indicating 75 device but it will be apparent that it is within the scope of our invention to operate this system otherwise than by electrical energy and to utilize indicating devices other than electric incandescent lamps. We prefer to carry out our invention by connecting 80 all the room check receptacles to one supply conductor of a source of electrical energy and to connect the other supply conductor to one terminal of a number of electrically operated indicators whose other terminals are each independently, through 85 a separate wire, connected to a terminal of a spring contact which is provided for each receptacle. The arrangement is such 90 that the closing of the spring contact completes the electric circuit so that each indicator is controlled by the spring contact of the corresponding receptacle. When a room check is inserted in the receptacle, the 95 spring contact is separated, the electric circuit broken and the indicator operated.

The indicators, so arranged that one indicator may not be confused with any other, may be contained within a few square feet 100 of surface and the indicators of equal priced rooms may be grouped together. A number corresponding to the number of the room represented by an indicator is placed thereon so that when the indicator is operated to show an empty room, the number will be readily visible. When a guest registers, the clerk refers to the collected indicators and determines at a glance which rooms of the guest's choice of price are va- 105 110

5
eant. More specifically, for our indicators, we prefer to use electric lamps so confined that the light from one lamp may not be confused with a light from any other. The 10 lamps may thus be contained within a few square feet of surface area and the lamps of equal priced rooms may be grouped together. A light transmitting plate is placed over the top surface of the lamps, preferably flush with the top of the register clerk's desk, and a number corresponding to the 15 number of the room represented by a lamp is placed on the plate immediately over the lamp so that when the lamp is lighted, the 20 number will be readily visible. If an assignment is made, the clerk may temporarily mark the indicator until the check clerk has had time to insert a check in the proper receptacle and thus to open the circuit of that particular indicator. The light 25 transmitting plate may be of ground glass to furnish a suitable surface upon which to place the temporary mark. The register clerk may thus dispose rapidly of a large crowd of prospective guests without error.

By means of a device for shorting out the check receptacles and clips, each indicator may be connected directly across the source 30 of energy and defective indicators be quickly detected. Where lamps are used, the shorting out device will show up burned out lamps and thus affords a ready means for testing out the system.

In the accompanying drawings, Figure 1 35 is a top plan view of an indicating means forming part of our invention; Fig. 2 is an enlarged fragmentary top plan view of the same; Fig. 3 is a sectional elevation of the view of Fig. 2; Fig. 4 is a side elevation of 40 a spacer part; Fig. 5 is a front elevation of a fragment of a room rack forming part of our invention; Fig. 6 is a sectional elevation on the line 6—6 of Fig. 5; Fig. 7 is a front elevation of a card holder; Fig. 8 is a section 45 on the line 8—8 of Fig. 7; Fig. 9 is a diagram showing electrical connections for carrying out our invention; Fig. 10 is a perspective view showing an arrangement of the parts comprised by our invention; 50 and Fig. 11 is a top plan view of the shorting-out device for a group of lamps.

Referring to the drawing, the room rack 10 is provided with card or check holders 11 and bolts 12 electrically insulated from 55 each other. Each bolt holds a metallic spring clip 13 so that it presses against and makes electrical contact with a single card or check holder, each card or check holder being cut away at 14 to prevent interference with clip and bolt for the card or check holder below and at 15 to permit ready access to its corresponding clip and bolt. Each card or check holder is in electrical contact with bus bars 16 which are 60 electrically connected together to one ter-

70 minal of the source of energy, for which we preferably use a transformer 17 although a set of batteries, a motor-generator or other source may be employed. Each bolt 12 is electrically connected through a wire 18 with one terminal of an incandescent lamp.

As shown in Figs. 1, 2 and 3, the indicating means 18' consists of a carrier bed 19 to which is fastened with the bolts 20 an electrically non-conducting block 21, described 75 more fully hereinafter, suitably spaced from the carrier bed by the spacing washers 22 to form a terminal chamber 23. Over the top of the block 21 is placed an electrically non-conducting plate 24 to which is attached 80 a metallic contact plate 25 which makes electrical contact with one terminal of every lamp 26 through the socket shell 27 and with the second terminal of the transformer. The second terminal of each lamp makes 85 electrical contact with similar contact bolts 28 electrically insulated from each other and also from the contact plate 25 by the non-conducting bushing 29 which with the contact bolt 28 serves to hold the socket shell 27 90 against the contact plate 25. Each contact bolt 28 is electrically connected to a bolt 12 on the room rack through the wire 18 previously described. Each lamp is confined within a section of the opaque crate-like 95 spacer 30 over which is placed a plate 31 of transparent or translucent material. For the plate 31, we preferably use ground glass. For ventilation, the spacer strips are cut away at 32 as shown in Figs. 3 and 4. A 100 number, corresponding to the room number in the room rack, is placed on the plate 31 over the lamp connected to the card holder bearing that number. The scheme of wiring is shown in Fig. 9 in which a transformer 105 is considered as the source of electrical energy. For convenience and economy a switch 33 may be inserted between the source of energy and the lamps. With the switch 33 turned on the lamp will be lighted 110 until a room card 34 is inserted in the holder 11 of the room rack when the electrical contact between the clip 13 and holder 11 is broken leaving the lamp unlighted. For 115 convenience, rooms of the same price may be grouped together thus greatly facilitating the search of the room clerk.

In order that the indicating means may be quickly and reliably checked, means have been provided to throw a group of lamps 120 directly across the line of the source of energy by shorting out the card holders and clips as shown in the wiring diagram of Fig. 9. In order to carry out this provision, the block 21 previously referred to, is recessed under each lamp and from front to back between alternate rows of lamps as shown in Fig. 11. A barrier remains between alternate rows and between the space under each lamp. A metallic conductor 125 35, 130

having attached on opposite sides pairs of spring contacts 36 spaced from each other according to the space between lamp centers, is placed in each lengthwise groove with a 5 spring contact 36 in a recess under each lamp. The conductors 35 are fastened at the back with a metallic bar 37 and at the front with a bar 38 having a handle 39. The bars 37 and 38 are preferably attached 10 so that when the bar 37 is brought against the block 21 the contacts 36 touch and make electrical connection with the bolts 28 and when the bar 38 is against the block 21 the contacts 36 are separated from the bolts 28. 15 A conductor 40 connects the bar 37 with that line of the source of energy which leads to the card or check holders. The plate 24 insulates the conductors 35 and contacts 36 from the metallic contact plate 25. 20 In operation, when a guest has specified the price he wishes to pay, the register clerk turns on the switch 33 and locates a lighted number in the group of rooms of the guest's choice of price. If he does not have such a 25 room, he knows at once what others at the next step in price are available. When the guest takes a room, the clerk puts a mark on the plate 31 over the lighted number until the card clerk has had an opportunity 30 to make out the card and insert it in the holder 11 to break the circuit for that particular lamp. The marks on the numbers may be removed by the card clerk at the time he inserts the card in the holder. To 35 check the indicating means for burned out lamps or other faults and errors, the handle 39 is pulled out permitting each lamp to be supplied with energy direct from the source. By lifting the plate 31, access may be had 40 to unlighted lamps which may be replaced readily by new lamps.

What we claim as new and desire to secure by Letters Patent of the United States, is:

1. The combination of a rack comprising 45 a plurality of receptacles for cards, a plurality of electrically operated indicators each corresponding to a receptacle and means whereby the insertion in or removal from the said rack of a card effects a change 50 in the electrical supply circuit of a corresponding indicator.

2. The combination of a rack comprising a plurality of receptacles for cards, an indicating means separate from said rack comprising 55 a plurality of indicators each corresponding to a receptacle and means whereby the insertion in or removal from said rack of a card effects a change in the electrical supply circuit of a corresponding indicator.

60 3. The combination of a rack comprising a plurality of receptacles for cards, a plurality of electrically operated indicators each corresponding to a receptacle, means whereby the insertion in or removal from 65 said rack of a card effects a change in the

electrical supply circuit of a corresponding indicator and means for individually supplying electrical energy when desired to a number of said indicators to test out their operativeness.

70 4. The combination of a rack comprising a plurality of receptacles for cards, a plurality of juxtaposed lamps each provided with means for restricting the direction of illumination therefrom and each corresponding to a receptacle and means whereby the insertion in or removal from said rack of a card effects a change in the electrical supply circuit of a corresponding lamp.

75 5. The combination of a rack comprising a plurality of receptacles for cards, a plurality of juxtaposed lamps each provided with means having a light transmitting cover plate for restricting the direction of illumination therefrom and each corresponding to a receptacle and means whereby the insertion in or removal from said rack of a card effects a change in the electrical supply circuit of a corresponding lamp.

80 6. The combination of a rack comprising a plurality of receptacles for cards, a plurality of electric lamps each corresponding to a receptacle, means whereby the insertion in or removal from said rack of a card effects a change in the electrical supply circuit 85 of a corresponding lamp, a source of electrical energy the first terminal of which is connected to the first terminal of said electric lamps and the second terminal of which is connected to said receptacles, and means for individually supplying the electrical energy when desired to a number of said lamps to test out their operativeness, said means comprising reciprocatable bars having thereon spring contacts said reciprocatable bars being electrically connected to the second terminal of said source of electrical energy and said spring contacts being electrically connected to the second terminal 90 of said electric lamps.

95 7. The combination of a rack comprising a plurality of receptacles for cards, an indicating means separate from said rack comprising a plurality of indicators each corresponding to a receptacle and means comprising 100 a metallic spring clip in electrical contact with said receptacle and capable of being electrically separated therefrom whereby the insertion in or removal from said rack of a card effects a change in 105 the electrical supply circuit of a corresponding indicator.

110 8. In an electrical circuit, the combination of a source of electrical energy, a plurality of electric lamps electrically insulated 115 from each other and means individual to each lamp for opening or closing the electrical supply circuit thereof comprising a card receptacle electrically connected to one terminal of the said source of electrical en- 120 130

ergy and a spring clip electrically connected to the second terminal of said source of electrical energy and adapted to be separated from said receptacle by the insertion of a card therein.

9. In an electrical circuit, the combination of a source of electrical energy, a plurality of electric lamps electrically insulated from each other, means individual to each lamp for opening or closing the electrical supply circuit thereof comprising a card receptacle electrically connected to one terminal of the said source of electrical en-

ergy and a spring clip electrically connected to the second terminal of said source of electrical energy and adapted to be separated from said receptacle by the insertion of a card in the latter and means for shorting out said receptacle and said clip to test out the operativeness of said indicators.

In witness whereof we have hereunto set our hands this 12th and 16th days of July, 1919.

FRANK P. BLAIR.
CHESTER L. DOWS.
GEORGE S. MERRILL.
